US00D598932S

(12) **United States Design Patent**
Ryu et al.

(10) **Patent No.:** US D598,932 S
(45) **Date of Patent:** ** Aug. 25, 2009

(54) **AUDIO**

(75) Inventors: **Dai Hyung Ryu**, Gyeonggi-do (KR);
Kyoung Joung Kim, Seoul (KR); **He Won Kihl**, Seoul (KR)

(73) Assignee: **LG Electronics Inc.**, Seoul (KR)

(**) Term: **14 Years**

(21) Appl. No.: **29/309,125**

(22) Filed: **Jun. 25, 2008**

(30) **Foreign Application Priority Data**

Jan. 25, 2008 (KR) 30-2008-0003807

(51) **LOC (9) Cl.** **14-03**

(52) **U.S. Cl.** **D14/496; D14/203.3**

(58) **Field of Classification Search** ..... **D14/496, D14/401, 435, 474, 483, 217, 137, 138, 160, D14/168, 356, 203.1–203.8, 507; 345/156, 345/169, 173–179, 905; 715/727–729, 864; 710/1, 5, 8; 713/1, 600; 455/1.1, 1.7, 73, 455/344–347, 93, 95, 3.01–3.06, 550.1, 573.1; 370/342–344; 369/1, 2, 6–12; 463/43–47; 273/148 B**
